UNITED STATES PATENT OFFICE

2,417,219

HIGH SIDE CUTOUT UNIT FOR SWITCHES

Burton E. Shaw, Bristol, Ind., assignor to Penn Electric Switch Co., Goshen, Ind., a corporation of Iowa

Application June 29, 1943, Serial No. 492,679

5 Claims. (Cl. 200—83)

1

My present invention relates to an actuating unit such as one operated by high pressure in a refrigerant line and effecting opening of a switch which is normally and otherwise controlled by changes in temperature or refrigerant pressure.

One object of the invention is to provide an actuating device of this general character which may be used in a variety of installations and which primarily comprises a unit having self contained pressure responsive means, an actuating lever operated thereby, a toggle spring for imparting snap action to the actuating lever, and an adjustable range spring for the actuating lever, which is adjustable while the unit is detached from a control switch or the like on which it is to be later installed.

Another object is to provide an actuating unit which may be installed on a control device when required, thus eliminating the necessity of the dealer stocking both control devices with the actuating unit and others without them.

A further object is to provide an actuating unit in which all the mechanism is mounted in a casing of substantially the size and shape of the usual bellows housing of a refrigerant motor control switch, such casing being readily attached as by four screws to the housing of a control switch in position for an actuating lever thereof to project into the housing and operate the main switch therein to "off" position upon an undesirable condition occurring, such as excessive pressure on the high side of the refrigerant compressor.

Still a further object is to provide an actuating unit having range adjusting means which can be adjusted while the unit is detached from a switch housing and thereby preset at the factory, so that it is merely necessary to attach it to the control device when a control device with the unit is desired for sale by the dealer, the unit having a range indicating scale and means to adjust a toggle spring and the range spring from the exterior of the unit casing.

With these and other objects in view, the invention resides in certain improvements and in a combination of parts of the device, all as will hereinafter more fully be described and the novel features will be pointed out in the claims appended to the application.

In the accompanying drawings:

Figure 1 is a front elevation of a switch such as shown in the application of Harold L. Hawthorn, Serial No. 492,678, filed June 29, 1943, with my high pressure cut-out unit mounted thereon;

2

Figure 2 is an enlarged plan view of the cut-out unit, omitting an actuating arm thereof;

Figure 3 is a vertical sectional view through the unit and looking upward in relation to Figure 2, and

Figure 4 is another vertical sectional view of the unit and looking toward the left in Figure 3.

On the accompanying drawing, I have used the reference numeral 10 to indicate generally a switch housing, from which the cover has been omitted. The housing 10, as shown, has a back plate and bottom and top plates 12 and 14. A bracket 16 is mounted in the housing 10 and carries a pivot pin 18. Pivoted on the pin 18 is an actuating lever 20 having an extension 22. For automatically moving the lever 20 and its extension 22 in response to a condition such as refrigerant pressure, I provide a bellows 24 opposed by a range spring 26. The bellows 24 is contained in a housing 28 with which a pressure connection can be made at a fitting 30. Secured to the head of the bellows is an operating stem 32 engaging the lower side of a pin 34 carried by the lever 20. Engaging the upper side of the pin is an end washer 36 for the lower end of the spring 26. An end washer 38 is provided for the upper end of the spring and it is non-rotatable relative to an adjusting screw 40, in the usual manner.

The lever 20 and its extension 22 are adapted to actuate a switch arm 42 through toggle spring and link mechanism, fully described in said Hawthorn application. This connection briefly includes a toggle lever 44 pivoted at V points 46 and connected by a toggle spring 48 to the lever extension 22, the lever 44 being connected by a toggle link 50 to the lower end of the switch arm 42, the upper end of the switch arm being pivoted at 52. The switch arm 42 carries a movable bridging contact 54 adapted to bridge a pair of stationary contacts 56. The bridging contact is mounted on a bar 58 extending loosely through the switch arm 42 and is urged in one direction relative thereto by a spring 60. The motion is limited by a pin 62. When the switch is in closed position, it may be opened while the linkage 44—48—50 remains in closed circuit position by engaging an extension 64 of the bridging contact 54 and pushing it toward the left, as will hereinafter appear.

My actuating unit comprises a casing 66 adapted to be secured to the lower wall 12 of the housing 10 by four screws 68. These screws pass upwardly through openings 70 formed in a flange

72 around the base of the housing 66 and are threaded into the wall 12.

Within the casing 66 is a frame 74 secured to a wall of the casing 66 as by two screws 76. The frame 74 has a pair of ears 78 for supporting a pivot pin 80. The frame further has a bottom plate 82 provided with an embossed central part having therein a perforation 84, as shown in Figure 4. A bellows housing 86 has a fitting 88 extending through the opening 84 and the bellows housing is thereby mounted in position relative to the frame 74, a lock nut 90 being screwed on the fitting for this purpose.

Within the housing 86, I provide a bellows 92 which is relatively small because it need respond 15 only to very high pressures. The bellows has an actuating stem 94 extended out of the upper end of the housing 86.

An actuating lever in the form of a plate 96 is pivoted to the pin 80, the plate having perforated 20 ears 98 for this purpose. The plate 96 further has a plurality of flanges 100, 102, 104 and 106. The flange 100 is adapted to contact the upper end of the bellows stem 94, and to effect such contact a range spring 108 is provided. The 25 upper end of the range spring is connected to the plate 96 and the lower end is mounted on a plug 110. An adjusting screw 112 is threaded in the plug and passes through an opening 114 in the plate 82, the screw having outside of 30 the opening a slotted head 116. The casing 66 has an opening 118 to receive the head 116 and permit free rotation thereof.

The plug 110 has an extension 120 terminating in a pointer 122. The pointer 122 travels 35 in a slot 124 of the casing 16 back of a transparent window 126. Suitable indicia are provided for cooperation with the pointer 122 to indicate the pressure at which the lever 96 will be moved to cut-out position, as shown in Figure 1.

For operating the lever 96 with snap action and to have a wide differential for its operation, so that after high side cut-out occurs, cut-in will not be permitted again until there is a substantial reduction in pressure in the bellows housing 86, I provide a toggle or over-center spring 128. Its ends are capped as at 130 and 132, the cap 130 engaging a knife edge lower end of the flange 102, and the cap 132 engaging an adjustable pivot 134. The pivot 134 is threaded in the frame bottom plate 82 and there is an opening 136 in the casing 66, permitting free rotation of the screw when adjusting it.

In Figure 3, I have shown a lever diagram for the over-center positions of the toggle spring 128. These are shown by dot and dash lines and the "on" position of the parts is shown in this figure. The "off" position corresponds to a center indicated by a black dot 138, where the pivot between the lower end of the flange 102 and the cap 130 occurs, after the high pressure cut-out has operated to "switch-on" position. The flange 102 is confined in a slot of the frame 74 having one side indicated at 140 and its other side indicated at 142. The sides 140 and 142 serve as stop surfaces for the flange 102 in the switch-on and switch-off positions of the actuating means.

The flange 104, when the actuating unit is mounted on the switch housing 10, extends upwardly through a slot 144 in the bottom wall 12, and an actuating arm 146, preferably of insulating material, is secured to the flange 106 by screws 148. The actuating lever is shown in the

5 switch-on position in Figures 1 and 3, and it will be obvious that when it is rotated counterclockwise the arm 146 will swing toward the left at its upper end to engage the extension 64 of the bridging contact 54, thereby separating one of the movable contacts from one of the stationary contacts to break the circuit until such time as the pressure in the bellows housing 86 recedes to a value permitting the spring 108 to overcome the spring 138 and return the actuating unit to its normal position.

The arrangement of parts of my device is such that the entire unit is a sub-assembly that can be attached or not relative to a switch unit, depending on whether a high side pressure cut-out is or is not desired. The device can be entirely fabricated and preadjusted at the factory, as it is unnecessary to have any cooperation between the unit and parts of the switch or control device to effect the adjusting operation. At the same time, the device is capable of being readjusted in the field as to range, the screw head 116 being accessible and upon rotation showing, by the pointer 122 just what the adjustment is by observance through the window 126. The differential of operation can also be increased or decreased by moving the screw 134 up or down, respectively.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. An actuating unit comprising a casing for attachment to a control housing, a frame in said casing, pressure responsive means within said casing and having a threaded fitting projecting through said frame and from said casing to the exterior thereof for attachment to a pressure line, a lock nut on said fitting for mounting said pressure responsive means relative to said frame, an actuating lever pivoted to said frame, a range spring connected to said actuating lever and having an adjusting screw carried by said frame and projecting through said casing for operation from the exterior thereof, said range spring normally effecting engagement of said actuating lever with said pressure responsive means, and a toggle spring interposed between said actuating lever and said frame to effect snap action of said actuating lever, said actuating lever, said range spring, said adjusting screw and said toggle spring being all mounted within said casing.

2. An actuating unit comprising a casing for attachment to a control housing, a frame in said casing, pressure responsive means mounted on said frame, an actuating lever pivoted to said frame, toggle means to effect snap action of said actuating lever, and a range spring connected to said actuating lever and having an adjusting screw carried by said frame, said range spring normally effecting engagement of said actuating lever with said pressure responsive means, said toggle means, said pressure responsive means and said range spring being arranged at the points of a triangle within said casing and their axes extending substantially parallel to each other.

3. An actuating unit comprising a casing for attachment to a control housing, a frame in said casing secured to one wall thereof, pressure re-

sponsive means mounted on said frame and having a fitting projecting from said casing, thru said frame and to the exterior of said casing for attachment to a pressure line, a retainer coacting with said fitting and said frame to retain the fitting and said pressure responsive means assembled relative to said frame, an actuating lever pivoted to said frame, a range spring connected to said actuating lever, said range spring normally effecting engagement of said actuating lever with said pressure responsive means, and toggle means to effect snap action of said actuating lever said pressure responsive means, said actuating lever, said range spring and said toggle means being located within said casing.

4. An actuating unit of the character described for a control device having a housing, said unit comprising a cup-like casing for direct attachment to the housing, pressure operated means comprising a bellows and a chamber therefor, an actuating element controlled by said pressure operated means and extending from said casing and into said housing for engaging said device upon operation of said pressure operated means, said actuating element including a bell crank having one arm engageable with said bellows, a spring connected with said arm to effect such engagement, said spring and the other arm of said bell crank extending substantially parallel to said chamber, and toggle spring mechanism aligned with said other arm of said bell crank for imparting snap action to said actu-

ating element, said bellows, its chamber, said spring and said toggle spring mechanism being all located within said cup-like casing.

5. In an actuating unit, a casing for attachment to a housing of a control device, frame in said casing, pressure responsive means in said casing and carried by said frame, an actuating element pivoted to said frame within said casing and projecting from the casing and into said 10 housing for moving a controlling device therein to a predetermined position upon operation of said pressure responsive means, adjusting means within said casing and carried by said frame for adjusting the range of operation of said pressure responsive means, said adjustment means having a manually actuatable part projecting to the exterior of said casing, and a fitting for connection with said pressure responsive means, said fitting being carried by said frame whereby the 15 frame, the pressure responsive means, the actuating element and the adjusting means form a 20 unitary structure independent of said casing.
